Specification for Design.

Patented July 1, 1913.

Application filed May 29, 1913. Serial No. 770,763. Term of patent 3½ years.

To all whom it may concern:

Be it known that I, ADOLPH PETZOLD, a citizen of the United States, residing in the city of Philadelphia, State of Pennsylvania, have invented a certain new, original, and ornamental Design for Rugs, of which the following is a specification, reference being had to the accompanying drawing, forming part thereof.

The figure is a half section of an Axminster rug, the other half section being identical therewith showing my new design.

I claim:

The ornamental design for a rug, as shown.
ADOLPH PETZOLD.
